[57] **CLAIM**

The ornamental design for a hand-held electronic game machine, as shown and described.

DESCRIPTION

FIG. 1 is a front perspective view of a hand-held elec-

tronic game machine of a first embodiment showing our new design;

FIG. 2 is a rear perspective view of the first embodiment;

FIG. 3 is a top plan view of the first embodiment;

FIG. 4 is a bottom plan view of the first embodiment;

FIG. 5 is a front view of the first embodiment;

FIG. 6 is a rear view of the first embodiment;

FIG. 7 is a right side view of the first embodiment;

FIG. 8 is a left side view of the first embodiment;

FIG. 9 is a front perspective view of a second embodiment;

FIG. 10 is a rear perspective view of the second embodiment;

FIG. 11 is a top plan view of the second embodiment;

FIG. 12 is a bottom plan view of the second embodiment;

FIG. 13 is a front view of the second embodiment;

FIG. 14 is a rear view of the second embodiment;

FIG. 15 is a right side view of the second embodiment;

FIG. 16 is a left side view of the second embodiment;

FIG. 17 is a front perspective view of a third embodiment;

FIG. 18 is a rear perspective view of the third embodiment;

FIG. 19 is a top plan view of the third embodiment;

FIG. 20 is a bottom plan view of the third embodiment;

FIG. 21 is a front view of the third embodiment;

FIG. 22 is a rear view of the third embodiment;

FIG. 23 is a right side view of the third embodiment;

FIG. 24 is a left side view of the third embodiment;

FIG. 25 is a front perspective view of a fourth embodiment;

FIG. 26 is a rear perspective view of the fourth embodiment;

FIG. 27 is a top plan view of the fourth embodiment;

FIG. 28 is a bottom plan view of the fourth embodiment;

FIG. 29 is a front view of the fourth embodiment;

FIG. 30 is a rear view of the fourth embodiment;

FIG. 31 is a right side view of the fourth embodiment;

and,

FIG. 32 is a left side view of the fourth embodiment.
